BARK CHIPPING HACK FOR TURPENTINING TREES

Albert G. Snow, Jr., Lake City, and Hubert R. Lanier, Olustee, Fla., assignors to the United States of America, as represented by the Secretary of Agriculture

Application February 23, 1945, Serial No. 579,477

1 Claim. (Cl. 30—121)

(Granted under the act of March 3, 1883, as amended April 30, 1928; 370 O. G. 757)

1

This application is made under the act of March 3, 1883, as amended by the act of April 30, 1928, and the invention herein described, if patented, may be manufactured and used by or for the Government of the United States of America for governmental purposes without the payment to us of any royalty thereon.

This invention relates to a turpentine hack for chipping bark from pine trees in the process of obtaining oleoresin, in particular where chemical stimulants are employed, and has among its objects the provision of a turpentine hack best suited to remove the bark only down to but not including any wood; that will make a cut through the bark to the wood in such a manner that the resulting cut surface is perpendicular to the axis of the tree, resulting in a minimum of thin living bark tissue that tends to die with chemical stimulation, thereby clogging up some of the horizontal duct system and inhibiting the flow of oleoresin; that will remove all the dead and living bark from a definite area above the face without leaving any residual tissue to inhibit the action of applied chemicals and/or the flow of oleoresin; that will result in specified limits in width of bark being removed in any one cut; that will not become clogged with bark when used on trees with thick bark, particularly in virgin operations; that, when used with an improved acid treatment of faces, in contrast to the conventional method of acid treatment of faces in which wood is removed, will result in greater yields of oleoresin; and that will cut only the bark and, when used in a conventional manner, can be operated with an expenditure of less energy.

In general, the hack is of the type provided with a longitudinally extending handle having a hack head attached to one end of the handle with sharpened edges of the head positioned to one side of the handle and directed forwardly toward the free end thereof so that in using the hack an operator grasps the handle and draws the hack head longitudinally toward himself with the sharpened forward edges engaging the bark, thus to chip it from the tree, leaving a cut surface or face on the tree. Such hacks are generally provided with a weight attached to the free end of the handle.

For a detail description of the invention, reference is made to the accompanying drawing, in which

Figure 1 is a three-dimensional view of the hack, partially showing the handle and with parts of the hack head cut away more clearly to represent the construction;

2

Figure 2 is a side view illustrating a variation of the hack head; and

Figure 3 is a three-dimensional view illustrating another variation.

5 The hack is provided with a longitudinally extending handle 10 of conventional type, to one end of which the hack head 11 is attached by known means.

The special features of the invention relate to 10 the construction of the hack head. This head is provided with two generally similar, facing, spaced, flat side members 12 and 13, member 12 being provided with a sharpened, straight, laterally extending edge 14, and member 13 with a 15 similar edge 15. Each side member is also provided with a straight end, this end making an acute angle with the sharpened edge. Angle α as shown in Figure 1 indicates this acute angle in reference to the side 13. The hack head also 20 comprises a flat end member 16 having a sharpened, straight, forward edge 17 and two straight, longitudinally extending ends making obtuse angles, one of which is shown at b, with its straight edge, end member 16 being joined to the side 25 members 12 and 13 as by an integral connection between the straight, longitudinally extending ends of the flat end member and the mating straight ends of the side members, as illustrated by the corners 18 and 19, respectively. The junctions between the end member 16 and side members 12 and 13 are such that the sharpened edges 14, 17 and 15 are contiguous and the angles between edge 14 and edge 17 and between edge 15 and edge 17, one of which is shown at c, are right 30 angles.

In using the hack, the sharpened edge 17 is 35 applied to the tree and severs the bark at the cambium. The sharpened edges 14 and 15 sever the bark down to the wood with a cut perpendicular to the axis of the tree.

The angles, one of which is shown at a, being acute, result in a slicing action when the hack head is drawn across the bark. This reduces the draw force necessary to make the cut. The angles, one of which is shown at b, being obtuse, result in rearward divergence of the side members 12 and 13. This reduces the tendency of the bark to jam between the side members during the cutting. The angles, one of which is shown at c, being right angles, result in symmetry so that an incision may be made with the entire edge 17 in contact with the wood, the bark incision made by edges 14 and 15 being perpendicular to the axis of the tree.

55 The variation shown in Figure 3 is similar to

that of Figure 1, except that the hack head is tilted forward. With this construction, angle *d* may be made more acute than the corresponding angle *a* in the variation of Figure 1 without increasing the overall amount of material used in constructing the head.

The variation shown in Figure 3 is similar to that of Figure 1, except that a notch as shown at 20 is cut out of the end member, thus further to reduce the tendency of the bark to jam between 10 the side members during the cutting operation.

Having thus described the invention, what is claimed is:

A hack having a longitudinally extending handle and a hack head for chipping bark from pine trees, said hack head comprising two generally similar, facing, spaced, flat side members each provided with a sharpened, straight, laterally extending edge and a straight end making an acute angle with the sharpened edge, and a flat end member having a sharpened, straight, forward edge and two straight, longitudinally extending ends, the sharpened edge of said flat end member making obtuse angles with its two straight, longitudinally extending ends, said flat end mem- 25

ber being joined along its two longitudinally extending ends to the straight ends of the side members with the sharpened edge of each side member and the sharpened edge of the end member contiguous and at right angles to each other, said hack head being attached to one end of the handle in such manner that the sharpened edges are positioned to one side of the handle and directed toward the free end thereof.
